UNITED STATES PATENT OFFICE.

CYRENUS WHEELER, JR., OF AUBURN, NEW YORK.

WIRE AND CORD TESTING MACHINE.

SPECIFICATION forming part of Letters Patent No. 244,962, dated July 26, 1881.

Application filed March 11, 1881. (No model.)

To all whom it may concern:

Be it known that I, CYRENUS WHEELER, Jr., of the city of Auburn, in the county of Cayuga and State of New York, have invented 5 a new and useful Device for the Testing of the Tensile Strength of Cord or Twine and Wire, of which the following is a specification.

My invention relates more particularly to the testing of the tensile strength of cord or 10 twine and wire such as is in general use upon self-binding harvesting-machines, and was suggested from the fact that an accurate knowledge of the strength of said material was necessary in order to secure the consumer of twine 15 and wire for binding purposes from fraud and imposition of an inferior article, as well as to avoid the delay and annoyance caused by the use of such from breaking and continuous effectual working when binding grain in the 20 harvest-field. I attain these objects by the mechanism illustrated in the accompanying drawings.

The several figures are drawn upon two sheets, and consist of— 25 Fig. 1, which is a front elevation; Fig. 2, a rear elevation of the working parts; Fig. 3, a side or edge view of the same; Fig. 4, a sectional view of the bearings of the shaft; Fig. 5, a view of the indexed quadrant or sector; Fig. 6, a view of the marker, and Fig. 7 an end view of the marker and section of the indexed quadrant.

Similar letters refer to similar parts throughout the several views. 35 A is a broad base or foot, having feet B B at either end, and supports at its central point the upright post C, which carries the working parts of my device. Near the upper end of the post C is secured, by means of the bolt Z 40 and the screws T T, an iron plate, D, having a hub or shell, e, and a supporting-hub, B', both of which pass completely through the post C, and a recess or seat at the center of its upper end for the admission of the supporting base of the indexed quadrant W.

Through the hub or shell e of the plate D passes a shaft, F, which is in diameter much smaller than the interior diameter of the hub, and between which and the inside of the hub 45 or shell e is interposed a series of friction-rollers, f f, as shown in Fig. 4, Sheet 2, said

rollers being thus placed to reduce the friction of the shaft to the smallest possible degree.

At one end of the shaft F is placed the grooved cord-sheave E, having a hook, Q, 55 fastened thereto by means of screws n, and a marker-mover finger, U. The cord-sheave E has also a hub, Z, through which and the shaft F passes the pin m, thus securing the sheave firmly in position. At the other projecting end of the shaft F is placed a disk, G, 60 having ratchet-teeth s throughout the greater portion of its circumference, as shown in Fig. 2. This disk G has its bearing against the slightly-projecting end of the hub or shell e. 65

Passing onto the shaft F, and riveted to the disk G by the rivets h h, is the pendulum-lever O, having a hub, t, through which and the shaft F passes the pin g, thus securing the position of the disk and the pendulum-lever. 70 The pendulum-lever O has secured to it, in a position determined from actual experiment, the pendulum-weight N, by means of the bolt P. At the center of the lower end of the pendulum-lever O is the leveling mark or notch o. 75

R is a weighted pawl, acting automatically upon the ratchet-teeth s of the disk G, and is protected from sudden jar or strain by means of the hub B' of the plate D, through which passes the bolt S, thus securing the proper 80 and firm position of the weighted pawl R.

i is a rubber bumper for the lower end of the pendulum-lever O to strike against when the weighted pawl R is released from the ratchet-teeth s. This rubber bumper i is secured in its proper position upon the upright post C by means of the bolt j.

k is a leveling pointer bent at right angles upon itself to admit of the passage between itself and the upright post C of the pendulum-lever O, and is secured to the center of the post C, and in proper perpendicular position by the screws x.

H is a grooved cord-sheave, having a hook, K, and a ratchet, I. Interposed between the 95 grooved cord-sheave H and the upright post C is the washer A', of sufficient thickness to bring the two cord-sheaves E and H in the same perpendicular plane. Through the sheave H, its ratchet I, the washer A', and the upright post C passes a bolt or stud, J, having a flattened head, v, between which and the

ratchet I is placed the actuating hand-lever L, which has a dog, M, attached thereto, and a short slot, w, at its lower end, the whole being held in working position by the nut u upon 5 the opposite side of the upright post C.

V V is a forked support fitting into a recess of the plate D, and firmly secured thereto by the screw l through the hole r. This support V V carries the indexed quadrant W, to which 10 it is attached, and which is marked off into divisions of five pounds and upwards, as seen in Fig. 5, said divisions being determined from actual tests, and regulated in accordance therewith. The indexed quadrant W when in 15 proper working position is placed immediately behind the outer end of the marker-mover finger D, as shown in Figs. 1 and 3. The indexed quadrant W carries a movable marker, X, which has a projecting pin, b, a friction-spring, 20 c, lugs p and q, and an index-point d constructed as shown in Figs. 6 and 7. This marker X is kept in place upon the quadrant by the lugs p and q, and by the action of the friction-spring upon the upper edge of the indexed 25 quadrant is thus secured from slipping either backward or forward of itself, remaining wherever it may have been carried by the marker-mover finger U when ceasing to act. It is also prevented from being thrown off the indexed 30 quadrant on the one hand by the projecting pin a attached thereto, and on the other hand by the interposition of the marker-mover finger itself.

Y represents the cord as attached to the 35 cord-sheaves E and H while undergoing a test as to its tensile strength.

Having thus fully described the several parts of my invention and their construction, I will now explain their operation.

40 I first level up the machine by bringing the notch or mark o, on the end of the pendulum-lever O, in accurate opposition to the leveling-pointer k, and then tie one end of the cord or wire to be tested to the hook Q of the cord-sheave E, and the other end to the hook K of the cord-sheave H. I now bring the hand-lever L with its dog M into action upon the ratchet I, and gradually press downward upon the hand-lever L. This action causes the cord-sheave H 45 to turn, and through its connection with the upper cord-sheave E, by means of the cord or wire Y undergoing the test, causes E to move 50 uniformly with it. As E is turned by said connection it carries with it the weighted pendulum-lever O and its weight N. As the pendulum-lever is carried away from its center of gravity the strain upon the cord or wire is in- 55

creased in direct proportion to its upward movement, until such time as the strain upon the cord or wire is so great as to cause it to break. At 60 this moment the self-acting weighted pawl R prevents the weighted pendulum-lever O from falling a greater distance than one notch of the ratcheted disk G, and thus prevents any disturbance by jar or otherwise of the record of the 65 marker X upon the indexed quadrant W.

During the above operation the cord-sheave E has carried with it the fixed marker-mover finger U, the point of which, bearing against the pin b of the marker X, serves to push the 70 latter along on the indexed quadrant W. It will thus be seen that wherever the marker may be at the time when the tensile strain upon the cord or wire has caused it to break, there it will remain a faithful recorder of the tensile strength 75 brought to bear upon the cord or wire during the testing operation.

Having thus described the construction and operation of my invention, what I claim as new, and desire to secure by Letters Patent, is— 80

1. The combination, in a machine for testing the tensile strength of cord or wire, of the indexed quadrant, the marker clasping said quadrant and moving over the same, the vibrating arm or finger for moving said marker, and the 85 weighted pendulum-lever for actuating said finger, substantially as described.

2. The combination of the plate D and hub or shell e with the friction-rollers f, shaft F, and weighted pendulum-lever O, substantially 90 for the purpose specified and set forth.

3. The combination of the weighted pendulum-lever supported on an upright post, with the rubber bumper i, and the leveling-pointer k, substantially as described, and for the purpose specified. 95

4. The combination of the ratcheted disk and weighted pawl with the shaft F and the weighted pendulum-lever O, substantially as described and set forth. 100

5. The upright post, having a broad base, and supporting the cord-sheaves, rubber bumper, leveling-pointer, shaft and friction rollers, plate and hubs, indexed quadrant, marker-mover finger and movable marker, ratcheted disk and weighted pawl, and weighted pendulum-lever, the whole constructed and combined with the hand-lever L and dog attached thereto for joint operation, substantially as described and specified. 105
